UNITED STATES PATENT OFFICE

OLIVER G. SIMMONS, OF LAKEWOOD, OHIO, ASSIGNOR TO THE NATIONAL TOOL COMPANY, OF CLEVELAND, OHIO, A CORPORATION OF OHIO

KNIFE FOR HULLERS

Application filed September 27, 1927. Serial No. 222,249.

This invention relates to hullers of the type commonly known as bar hullers, and has for its principal object to provide a knife for use with such hullers which is exceptionally inexpensive to manufacture as compared with knives at present employed.

The knife embodying the present invention is a modified form of that disclosed in my co-pending application Serial No. 222,250, filed Sept. 27, 1927. Inasmuch as the manner of attaching and securing the knives to the cylinder and concave is clearly disclosed in the said application, it is not believed necessary to illustrate that portion of the huller in the present instance as the invention relates entirely to the structure of the knife.

It is commonly known that knives employed in hullers are provided with a plurality of cutting edges and the knives are so disposed in the cylinder and concave that all of the edges can be employed at different times by merely reversing the position of the knives within their associated grooves. In view of the fact that these knives are not sharpened for further use inasmuch as the expense in connection with the purchase of new knives is less than that involved in sharpening the used knives, new knives are consequently purchased. This involves considerable expense and adds considerably to the overhead in connection with the operation of the huller. It will be apparent, therefore, that any saving in labor in connection with the manufacture of the knives will result in a saving in cost, and in view of the great quantities of knives used, such an item is of material importance. It is, therefore, a further object of the invention to provide recesses on the opposite sides of the knives which can be provided by grinding or otherwise and which recesses serve to receive a member for retaining the knives properly within their associated grooves within the cylinder or concave. Such a construction is quite an improvement over the types of knives generally employed inasmuch as the latter include a longitudinal groove extending throughout the entire length of the knives and upon opposite sides, which requires machining and involves additional labor.

To effect a further saving in production cost the knives may be made of substantially one-third the amount of material required in the production of the customary type of knife by providing a filler or backer member adapted to rest within the base of the groove formed upon the cylinder and concave with which the knives are adapted to engage. This construction is clearly disclosed in the application above referred to.

With the objects above indicated and other objects hereinafter explained in view, my invention consists in the arrangement of the specific knife herein disclosed.

Referring to the drawings—

Fig. 1 is a longitudinal cross sectional view of a huller knife;

Fig. 2 is a front elevational view of the same;

Fig. 3 is a cross sectional view taken through one of the recesses and showing the manner in which the means for retaining the knives within the grooves of the cylinder and concave engages with the recesses in the knives;

Fig. 4 is a front elevational view of a modified form of the knife; and

Fig. 5 is a cross sectional view taken through the recesses of the knife in Fig. 4 and showing the filler or backer member which makes possible a reduction in the depth of the knife.

In the drawings, 10 indicates a knife which is adapted to be disposed within a groove provided in a cylinder or concave of a huller, the construction of which is not shown as the same is fully disclosed in my co-pending application above referred to. This knife 10 is formed of tool steel, and, as shown in the drawings, is a relatively flat bar of rectangular cross section. The knife is provided with a plurality of cutting edges 11 extending throughout the length of the bar. The knife is reversible in such a manner that all of the cutting edges may be employed at different times by merely reversing the bar from end to end or from front to back. The knife is retained within the groove provided in the cylinder or concave by any suitable means, the means here indicated being a bolt 12.

which has screw-threaded engagement with a suitable opening in the cylinder or concave. Beneath the head of the bolt 12 is a cylindrical washer or other member 13 which is adapted to engage in this instance one of a plurality of recesses 14 provided upon opposite sides of the knife, as shown in Figs. 2 and 3. It should be here noted that these recesses may be provided by grinding or other means which require only a short period of time compared with the time required to provide a longitudinally extending groove as is customary in knives of this type, and that these recesses further function as efficiently as the before mentioned longitudinal grooves.

If desired, the knife 11 may be constructed as illustrated in Fig. 4, in which case about one-third of the metal required to produce the knife illustrated in Fig. 1 is saved, which, 20 it will be noted, materially lessens the production cost of the knife.

Furthermore, the blade 10^a may be provided with a plurality of pairs of recesses 14^a, as clearly shown in Fig. 4, each pair being positioned adjacent the end of the knife and an equal distance from its adjacent cutting edge 11^a. Furthermore, the recesses 14^a should be similarly provided and positioned upon the opposite side of the knife directly opposite the recesses 14^a first referred to. As before stated, these recesses 14^a may be provided by grinding or otherwise, and in order to securely lock the knives within their associated grooves provided in the cylinder and concave, a bolt 12^a is adapted to have threaded engagement with a suitable opening in the cylinder or concave. A washer or other suitable member 13^a is adapted to be positioned beneath the head of the bolt 12^a and a portion 30 thereof extends into engagement with the lower recesses 14^a, as clearly shown in Fig. 5. In view of the fact that the depth of the knife 10^a has been materially lessened, a filler or backer block 15 is adapted to be positioned 40 within the bottom of the grooves of the cylinder and concave which is of sufficient height to properly position the cutting edge of the knife for operation when said knife is in engagement with the filler member 15.

50 In view of the enormous quantities of knives manufactured for replacement purposes in these hullers, and, further, in view of the fact that these knives are used only once before they are discarded, any savings 55 in cost of production will be of material advantage and will result in a decreased expense or overhead in connection with the operation of the hullers.

Having thus described my invention, I 60 claim:

1. A knife for hullers and the like comprising a relatively flat metal bar of substantially rectangular cross section having cutting edges extending substantially the 65 length of the bar and located on the opposite

longitudinal edges of the bar on a side thereof, said bar also having a pair of recesses arranged in the side adjacent the cutting edges, said recesses being arranged on opposite sides of a plane perpendicular to the 70 side of the bar and midway between the cutting edges thereof, said recesses further being arranged equidistant from their adjacent cutting edge, whereby the bar may be used reversibly in knife channels of greater 75 depth than the width of the bar.

2. A knife for hullers and the like comprising a relatively flat metal bar of substantially rectangular cross section having cutting edges extending substantially the 80 length of the bar along the longitudinal edges on a side thereof, said bar also having a pair of recesses adjacent each end thereof and arranged in the side of the bar upon which the cutting edges are located, the recesses 85 of each pair being arranged on opposite sides of a plane perpendicular to the side of the bar and midway between the cutting edges thereof, said recesses being also arranged equidistant from their adjacent cutting edge 90 whereby the bar may be used reversibly in knife channels of greater depth than the width of the bar.

3. A knife for hullers and the like comprising a relatively flat metal bar of substantially rectangular cross section having cutting edges extending substantially the 95 length of the bar from each corner thereof, the said bar also having a pair of recesses adjacent each end and on each side thereof, the recesses of each pair being arranged on opposite sides of a plane perpendicular to the side of the bar and midway between the cutting edges, said recesses being also arranged equidistant from their adjacent cutting edge 100 whereby the bar may be used reversibly in knife channels of greater depth than the width of the bar.

4. A knife for hullers and the like comprising a relatively flat metal bar of substantially rectangular cross section having cutting edges extending substantially the length 110 of the bar from each corner thereof, said bar also having a pair of recesses adjacent each end and on each side thereof, each pair of recesses being directly opposite a pair of recesses on the opposite side of the bar, the recesses of each pair being arranged on opposite sides of a plane perpendicular to the side of the bar and midway between the cutting edges, said recesses being further arranged equidistant from their adjacent cutting edge. 115

In testimony whereof, I hereunto affix my signature.

OLIVER G. SIMMONS.
